EDUCATIONAL DEVICE

Filed Oct. 11, 1929

Fig. 1.

UNITED STATES PATENT OFFICE

FRANK J. SEWALL, OF COLUMBIANA, OHIO

EDUCATIONAL DEVICE

Application filed October 11, 1929. Serial No. 398,997.

An object of my invention is to provide a mechanical device or means by which, for teaching purposes, mathematical operations can be performed both arithmetical and algebraical, by exhibiting problems and answers, for example, and which is inexpensive and easily operated, and which in its construction and manipulation will be attractive or inviting to children and which will be suitable for use in the home as well as in school rooms.

My invention consists in whatever is described by or is included within the terms or scope of the appended claims.

15 In the drawings:—

Fig. 1 is a perspective view of a teaching device embodying my invention with a portion of the outer casing broken away and internal parts shown in dotted lines;

20 Fig. 2 is a vertical section thereof;

Fig. 3 is a detail view in perspective of the band feeding device and the symbol plates carried thereby.

25 Fig. 4 is a detail view in section showing an arrangement for the use of electric lights as a substitute for the blind device.

Describing the embodiment of my invention shown in the drawings it comprises a rectangular cabinet or casing, 10, within which at top and bottom are journaled horizontal parallel rollers, 11, over and between which extends an endless band or apron, 12, of suitable inexpensive flexible material upon the outer surface of which are numbers in three spaced apart vertical columns, the numbers of the respective columns alining horizontally and the numbers in each horizontal row having an arithmetical or mathematical relation such as the multiplier and multiplicand and the product, that is to say that relation which members have in the performance of arithmetical or algebraical operations. Some of the alining numbers may be

40 algebraical. While one device or appliance may have provision for a large number of mathematical operations, my invention may be embodied in a device providing for a less number, this matter being regulated by the 45 school or teaching age of the pupils.

In the upper part of the casing front is a reading or display opening, 13, which extends horizontally from side to side to and past which the numerals or symbols on the endless band are moved step by step or intermittently 55 as by means of a vertical pawl-carrying bar, 14, situated close to one side of the casing or cabinet, preferably the right-hand side and capable of vertical reciprocation so that its lower pawl-forming end, 15, may engage 60 with ratchet teeth, 16, at that end of the lowermost roller, 11. By this pawl and ratchet device, the symbol-carrying band or apron is moved by one reciprocation of the pawl bar, 14, far enough to bring a horizontal row 65 of symbols opposite the sight opening, 13, to leave them at rest there for reading.

To reciprocate the pawl-carrying bar, 14, it has a handle, 17, attached to it which includes a knob which is situated at the front 70 of the casing close to the side thereof. This situation is to enable pawl bar, 14, to be actuated as by a teacher so that no portion of his body need be in front of the device and so cover what appears at the reading or sight 75 opening.

Inasmuch as it may be desirable to rapidly move the symbol-carrying band or apron and for an indefinite extent, I provide a turning knob, 18, on the right side of the 80 casing which is connected with the shaft or pivot of the lower roller, 11, and which may turn it in either direction. If needful the pawl bar may be lifted by its handle from the ratchet.

For stating the problems to be solved, but two of three alining numbers or symbols are exposed at the sight opening, 13, and then afterwards the third numeral or symbol which gives the solution is exposed, the solution then appearing being first covered by a blind that consists of a plate which carries on its face a question mark or interrogation point and that blind is attached to and movable with the pawl bar, 14, so that by the retracting or non-feeding movement of the bar, 14, the blind is moved from over the solution and its return to concealing position is simultaneously effected by the feeding movement of the pawl bar 14, for stat- 100

ing or presenting a fresh problem to be solved.

In the embodiment of my invention shown in the drawings, the blind consists of two plates, 19, placed vertically flatwise of one another and slidable one over the other so that oppositely extending horizontal slots, 20, in the respective plates may be placed one over the other producing a comparatively short opening and they may be drawn out producing a long opening and exposing when so drawn out, the interrogation or question mark on each. When they are slid together only one interrogation mark appears. Said plates, 19, are carried by and are horizontally slidable crosswise of an open frame, 21, which is attached to and extends horizontally from the upper end of the pawl-carrying bar, 14, and which has a length such that the blind plates may be shifted into cooperative relation with any desired vertical row or rows of numerals or symbols on the band or apron.

Situated forward of the blind plates and their supporting frame is a plate, 22, that is slidably secured to the inner side of the casing front or cover so that it may be moved vertically to place in alinement with the sight opening, 13, and the slots, 20, of the blind plates, anyone of an assortment of slots, 23, formed in the plate in horizontal groups of three, one above the other, such slots of two groups being disposed relatively to one another according to the arithmetical operation to be performed, and the slots of the third group being lengthened to expose the symbols of an algebraic problem, which symbols are longer than the mere numerals for an arithmetical operation. To enable both multiplication and addition or their equivalents to be performed in the same device, it is necessary to have certain of the numerals, used in those respective operations, in different columns that extend over the apron in different vertical planes, these columns being spaced laterally apart and for that reason the slots, 23, for multiplication and addition are placed out of alinement vertically as clearly shown in Fig. 1 of the drawings, so that they will cooperate with their respective columns of numerals.

For sliding the plate 22, vertically to expose the several groups of slots, 23, at the sight opening, 13, I attach to the plate near each side a button, 24, which extends outward through a vertical slot, 25, in the front wall for access and said button is preferably a clamping device so that the two buttons may be used to clamp or fix the plate, 22, in the desired vertical position.

To aid in readily locating the laterally shiftable blind plates, 20, for the purpose of placing the question mark properly, the upper edge of the slot-carrying plate, 22, is marked with index lines, 22a, with which

an index on said plates cooperates. The upper edge of the plate, 22, with its indexes is exposed at the time the lateral shifting or adjustment of blind plates 20, is to be performed, in order to enable the fingers to be passed through the reading slot, 13, to engage said blind plates, 20, without obstruction from plate, 22.

The index marks may be colored red and green to indicate, respectively, addition or subtraction and multiplication and division.

My teaching device may be advantageously used to teach percentage that is to say the finding of base rate and percentage. The pupil having become familiar with multiplication and division through manipulation of the device readily understands how to use it in the operation of finding the base when rate and per cent are known; to find the rate when base and per cent are known, and to find percentage when the base and rate are known. In the case of percentage parts of the belt having percentage problems are exposed and the required indicia are covered or disclosed.

Instead of using a blind in the sense of an opaque body movable over and away from the symbol, an arrangement such as shown in Fig. 4 may be employed which includes an electric light placed in rear of the front run of the symbol-carrying apron in the case of each column of numerals or symbols, each light 26 having a hand switch, 27, in its circuit for cutting it into and out of circuit and for each light circuit there is an automatic switch that includes in the case of each light a contact, 28, on a horizontal bar, 29, attached to the upper end of the pawl bar 140. The two lights for the factors or members of the problem are cut in circuit by their hand switches, 27, and the light for the problem solution has its switch, 27, turned to break the circuit and accordingly while the other two lights illuminate their respective symbols to present the problem, the light for the solution is cut in circuit only when the solution to the problem is to be revealed, the action thus corresponding to the action of the opaque blind device.

What I claim is:—

1. An educational device comprising a movable carrier of mathematical symbols arranged in a plurality of groups, the symbols of a group being in alinement crosswise of the direction of movement of the carrier and including a symbol to state a problem and its answer, means to display in succession less than all the symbols of a group to state a problem and certain of the remainder of them to give the answer and selective means to determine which symbol or symbols less than all of a group shall be displayed comprising an apertured member shiftable at will into cooperative relation with different ones of said symbols.

2. An educational device comprising a movable carrier of mathematical symbols arranged in a plurality of groups, the symbols of a group being in alinement crosswise of the direction of movement of the carrier and including a symbol to state a problem and its answer, means to display in succession less than all the symbols of a group to state a problem and certain of the remainder of them to give the answer and selective means to determine which symbol or symbols less than all of a group shall be displayed, comprising a blind shiftable to different positions along the line of the symbols of a group, and means to move said blind from symbol concealing position to symbol-displaying position.
3. An educational device comprising a movable carrier of mathematical symbols arranged in a plurality of groups, the symbols of a group being in alinement crosswise of the direction of movement of the carrier and including a symbol to state a problem and its answer, means to display in succession less than all the symbols of a group to state a problem and certain of the remainder of them to give the answer selective means to determine which symbol or symbols less than all of a group shall be displayed, and means simultaneously to shift said carrier to remove one group from a display position and another group to display position and prevent exhibition of the answer in the group newly shifted to display position.
4. An educational device comprising a movable carrier of mathematical symbols arranged in a plurality of groups, the symbols of a group being in alinement crosswise of the direction of movement of the carrier and including a symbol to state a problem and its answer, means to display in succession less than all the symbols of a group to state a problem and certain of the remainder of them to give the answer and selective means to determine which symbol or symbols less than all of a group shall be displayed, a blind shiftable to different positions along the line of the symbols of a group, and common operating means to move said carrier and said blind.
5. An educational device comprising means to display a mathematical problem and its solution in succession, including a symbol carrier containing a plurality of such problems and their solution, means to move the carrier step by step, and means to move said carrier continuously at different times.
6. An educational device comprising means to display a mathematical problem and its solution in succession, including a symbol carrier containing a plurality of such problems and their solutions arranged in parallel rows, the carrier being movable crosswise of the rows, and selective means to present selected symbols of a row in display position comprising an apertured member shiftable at will into cooperative relation with different ones of said symbols.
7. An educational device comprising means to display a mathematical problem and its solution in succession, including a symbol carrier containing a plurality of such problems and their solutions arranged in parallel rows, the carrier being movable crosswise of the rows, and a blind movable crosswise of the rows and adjustable to lengthen or shorten its effective area.
8. An educational device comprising means to display a mathematical problem and its solution in succession, including a symbol carrier containing a plurality of such problems and their solutions arranged in parallel rows, the carrier being movable crosswise of the rows, a blind device, and a carrier for it movable crosswise of the rows on which carrier said device is shiftable lengthwise of the rows.
9. An educational device comprising means to display a mathematical problem and its solution in succession, including a symbol carrier containing a plurality of such problems and their solutions arranged in parallel rows, the carrier being movable crosswise of the rows, and a movable member having a plurality of display openings said member being shiftable to interchange the positions of such openings.
10. An educational device comprising means to display a mathematical problem and its solution in succession including a symbol carrier containing a plurality of such problems and their solutions arranged in parallel rows, the movement of the carrier being crosswise of the rows, a blind device comprising a frame extending parallel with the rows and slotted plates slidable on said frame in the direction of length of the rows and with reference to one another and means to move said carrier crosswise of a row.
11. An educational device comprising a casing having a sight opening, a symbol carrier in the form of a traveling band, the symbols being in groups, the symbols of a group extending crosswise of the direction of movement of the band and the groups extending in the direction of movement of the band, hand-operated means to move the band to present the groups in succession at the sight-opening, a blind connected with such means and thereby shiftable to and from the sight opening and a plate with groups of display slots interposed between the blind and the sight opening and shiftable to selectively place such groups of slots at the sight opening.
- In testimony whereof I hereunto affix my signature.
